Inventor
Paul P. Binkis
By his Attorney
George C. Heinrich

UNITED STATES PATENT OFFICE.

PAUL P. BINKIS, OF GREENPORT, NEW YORK.

RING KNIFE.

Application filed May 4, 1921. Serial No. 466,672.

To all whom it may concern:

Be it known that I, PAUL P. BINKIS, a citizen of Lithuania, residing at Greenport, county of Suffolk and State of New York, have invented certain new and useful Improvements in Ring Knives, of which the following is a specification.

This invention relates to improvements in cutters, particularly twine or thread cutters and it is the principal object of the invention to provide a cutter of this kind which can conveniently be carried on one of the fingers of the operator.

A further object is to provide a cutter with means for guiding the knife blade into and out of its operative position and for locking it in either its operative position or in its position of rest.

For further comprehension of the invention, and of the objects and advantages thereof, reference will be had to the following description and accompanying drawing, and to the appended claims in which the various novel features of the invention are more clearly set forth.

In the drawing—

Figure 1 is a side view of a ring equipped with a cutting device constructed according to the present invention.

Figure 2 is an end view of such a ring, partly in section.

Figure 3 is a detail side view of a knife blade and its guide, and Fig. 4 is an edge view thereof.

The ring 10 of the customary form and made of any suitable material has a crown 11 which is slotted to provide a vertically disposed longitudinal slot 12. The knife 13 has an upper guide 14 by means of which it is slidably supported upon the upper edge of the crown with its blade guided within the slot 12.

The knife 13 has a curved cutting edge 15 on one side and a lower horizontal slot 16 45 near its lower edge in which a pin 17 travels

which is transversely passed through the crown to limit the lateral movement of the knife blade in one or the other direction.

Above said horizontal slot the knife blade is provided with two square openings 17 50 and 18 communicating with similar openings in the outer walls of the crown for the reception of a pin 18' which will lock the knife in either its operating position indicated in dotted lines in figure 2, or in its re- 55 tracted position of rest between the two parts of the crown formed by slot 12.

The device operates as follows:

When it is desired to use the knife 13, the pin 18' is removed from one of the openings 60 in blade and crown and the knife blade is laterally projected by taking hold of its guide 14 over one of the edges of the crown and the pin 18' is then placed into the other of the openings.

In order to lock the knife with its blade in its position of rest within the slot of the crown the foregoing operation is reversed.

Having thus described my invention what I claim as new and desire to secure by Letters Patent of the United States, is—

A device of the class described comprising a ring, a slotted crown on said ring, a knife blade having a lateral cutting edge guided in the slot of said crown, an upper 75 guide on said knife resting on the upper edge of said crown, said knife having a longitudinal horizontal slot, a pin adapted to travel in said slot for limiting the lateral movement of said blade in either direction, said blade 80 having two perforations above said horizontal slot for the reception of a pin for locking said knife blade in its operative position projected over the lateral edge of said crown, and in its retracted position of rest within 85 the slot of said crown.

In testimony whereof I have affixed my signature.

PAUL P. BINKIS.
